UNITED STATES PATENT OFFICE.

WILLIAM P. MARTYN, OF HARRISBURG, OREGON.

BALING-PRESS.

SPECIFICATION forming part of Letters Patent No. 393,116, dated November 20, 1888.

Application filed February 21, 1888. Serial No. 204,849. (No model.)

To all whom it may concern:

Be it known that I, WILLIAM P. MARTYN, of Harrisburg, in the county of Linn and State of Oregon, have invented a new and useful Improvement in Baling-Presses, of which the following is a specification.

My invention is an improved baling-press; and it consists in certain features of construction and novel combinations of parts, as will be hereinafter described and claimed.

In the drawings, Figure 1 is a perspective view of the improved press, the traverser or plunger being in its inner position and the press-box closed and secured by the clamping-bars. Fig. 2 is a top plan view of the machine, the plunger being shown in its outermost position and the cover-sections of the press-box being opened. Fig. 3 is a bottom plan view of the press-box end of the machine, 20 the motion of the latching devices being indicated in dotted lines. Fig. 4 is a detail side view illustrating the drop-gate of the press-box and the latching devices therefor. Fig. 5 is a detached cross-section of the top of the 25 press-box, the cover-sections being closed and secured by the clamp-bars. Fig. 6 is a similar view, the clamp-bars being removed and the cover-sections opened, forming a hopper for the press-box. Fig. 7 is a cross-section on 30 about line $x-x$, Fig. 2, drawn alongside of and showing the latch for the toggle-arms, in connection with such arms held by said latch, also showing the pulleys for the cords which connect the toggle-arms with the operating devices. Fig. 8 is a detached section on about 35 line $y-y$, Fig. 2. Fig. 9 is a detached horizontal section drawn through the windlass-pulley above the brake-levers and looking down thereon, and Fig. 10 is a detached vertical section drawn through the brake-blocks.

The main frame supports the press-box A at one end, has the windlass-shaft B journaled to it near its opposite end, and is provided between said press-box and shaft with a cross 45 guide-frame, C, for the toggle-arms, which frame extends beyond the sides of the main frame, as shown.

The guide-frame has top and bottom bars, c' , the latter serving as a support on which 50 the toggle-arms slide in their outward and inward movements. These toggle-arms D are

pivotedly connected to the framing and the plunger, and have their joint-bars d connected by ropes E E with the windlass G, said ropes passing inward from the joint-bars d over 55 guide-pulleys $e-e$, and thence back to the windlass, to which they may be secured in any suitable manner.

To the framing is pivoted the toggle-latch F, provided with shoulders f , which, when 60 the latch is properly turned, engage on opposite sides of one pair of the toggle-arms when the latter are closed, and serve to lock the toggles and secure the plunger in its innermost position when so desired. Thus after 65 the bale has been pressed properly it may be secured until it is properly tied, when by releasing the latch the rebound of the bale will throw the plunger back, open the toggle-arms, and leave such parts in position for another 70 operation.

In order to facilitate the operation of the latch F, I provide it with a crank-arm, F', to which is connected a rearwardly-extended handle-rod, by which the latch may be operated from the end of the machine. The edges of the latch outside of the shoulders f , at f' , are beveled, so that the toggle-arms in their inward movement will lift the latch and pass into engagement with the shoulders of the 80 latch. To permit this movement of the latch by the toggle-arms, I pivot its ends within vertically-elongated slots f'' , so the latch may rise slightly to enable the toggle-arms to pass under the portions f'' of the latch. To the 85 windlass G is fixed the pulley or drum H, on which the draft-rope I is secured. This draft-rope passes under the pulley and thence through a guide, J. The team or other power may be connected to it in any suitable manner.

I form the pulley with its outer or rim portion at h thicker than the adjacent inner portion, and arrange on opposite sides of such pulley levers K, pivoted at k , having their 95 short arms provided with shoes k' to engage the pulley H, and their long arms k'' extended rearwardly, such arms being connected by cross-bar k'' , fixed to one of the levers and movable through or past the other one.

It will be noticed that the brake-blocks are arranged to be engaged by the rear pair of tog-

gle-arms and pressed thereby into engagement with the pulley H when said toggle-arms are straightened out in their innermost position. When so adjusted, the toggle-arms cause the 5 brake-blocks to press against and stop the pulley when the bale is pressed. The brake-blocks are preferably made smaller at the top than at the bottom, or beveled from top to bottom, and the toggle-arms also beveled or rounded where 10 they engage the brake-blocks, so such blocks may be readily pressed downward to free them from braking-pressure against the pulley. This releasing of the brake may be easily accomplished by lifting the outer ends of the le- 15 vers K.

The plunger L is provided on its rear side with arms l, which extend rearwardly through guide-openings m in cross-bars M, and so steady and guide the movement of the plunger. 20 The top or cover of the press-box is formed of two similar sections, N, hinged at their outer edges, so they may be opened, and so form a hopper for use in filling the press-box with the loose material to be baled. When closed down, 25 the cover is secured by clamp-bars O, fitted at one end in loops or keepers P, and having their other ends held by loops or catches p, hinged to the framing and turning up over the ends of the clamp-bars, as shown. By releasing the 30 hinged catches the clamp-bars may be removed and the press-box refilled, as required.

In the under side of the press-box is provided a discharge-opening closed by a hinged drop-door, Q, which is provided at its movable or swinging end with a bar, q, or other suitable portion, fitted to be engaged by the latches r, arranged at the opposite sides of the machine. These latches are pivoted at their upper ends and adapted at their lower ends to 35 secure the door Q.

To the framing underneath the press-box I pivot two levers, R, which extend at their outer ends in rear of the latches r, and are connected therewith by a rod or similar connection, r'. 45 The inner ends of these levers are connected with an operating lever or levers, so they may be simultaneously operated to adjust the latches into or out of engagement with the door Q. By preference, the connection of such levers is effected in the manner most clearly shown in Fig. 50 3, and which I will now describe. In such construction levers R R are pivoted to the framing, and are connected by links s with a lever, S. Thus it will be seen the levers R are connected through the intervention of the lever S and links s. By extending the ends of the lever S to the opposite sides of the press the latches may be readily operated thereby from either side of the machine; but it is preferred 55 to extend such lever to but one side of the press and to employ a supplemental lever, S', and link s', by which the latches may be operated from the opposite side.

It will be noticed that the toggle-arms D at 60 their meeting ends on each side are geared together at D'. This gearing prevents such ends

of said arms from slipping past each other and preserves the joint-bars d at all times in proper relation to the toggle-arms which they connect.

When the bale is pressed and the plunger withdrawn, the latches r may be released, when the bale will fall through the discharge-opening, the door be closed and latched, and the operation proceed as before.

To the under side of the press is pivoted one end of a stake, T, which may be lowered at its other end to engage the ground and prevent any backward movement of the machine by the draft on the rope for drawing up the toggle arms. A loop or keeper, t, is provided for securing the stake elevated in moving from place to place.

The machine may be used for baling while traveling or moving by keeping a pair of 85 horses on the tongue and another to press the bale, and can in such way be used to bale from a cock or windrow.

Having thus described my invention, what I claim as new is—

1. In a baling-press, the combination of the plunger, the windlass-pulley, toggle-levers, and connections between said plunger and windlass, whereby the turning of the latter will effect an operation of the former, and the 95 brake shoe or shoes movable into and out of engagement with the pulley and arranged to be engaged by the toggle-levers, substantially as set forth.

2. The combination, with the pulley and the 100 toggle-arms connected therewith and having their inner edges or faces rounded off, of the brake-blocks, beveled as described, and the levers supporting said brake-blocks, substantially as set forth.

3. The combination, in a baling-press, of the main frame, the windlass, the pulley thereon, the brake-levers pivotally supported on opposite sides of the pulley and having brake-shoes at one end, the cross-bar connecting the opposite ends of the levers, and the guide J, provided with arms j, for supporting the rear ends of the brake-levers, substantially as set forth.

4. The combination, in a baling-press, of the plunger, the toggle-arms connected therewith, 115 means for operating said toggle-arms, and the latch having shoulders whereby to engage said arms when closed, substantially as and for the purposes specified.

5. In a baling-press, the plunger, the toggle-arms, and the main frame, combined with the latch F, having shoulders f and beveled portions f', and the vertically-elongated bearings for the ends of said latch, all combined and adapted for use substantially as set forth.

6. The combination, in a baling-press, of the toggle-arms, the framing, the plunger, the latch pivoted to the framing and having shoulders f, the crank-arm extended from said latch, and the handle-rod connected with such crank-arm, all substantially as and for the purposes specified.

7. In a baling-press, the combination of the main frame, the cross-bars M, having openings m, the press-box, the plunger having rearwardly-extended arms l projected through the openings m, the toggle-arms connected with said plunger and with the main frame, and means for operating said arms, substantially as set forth.

8. The combination, in a baling-press, of the framing, the plunger, the toggle-arms connected with said framing and plunger, the windlass-shaft and pulley, the independent cords connecting such windlass with the opposite pairs of toggle-arms, the guide-pulleys for such cords, and the draft-cord connected with the windlass-pulley, substantially as set forth.

9. In a baling-press, the combination of the framing, the plunger, the toggle-arms, a pulley, and a brake shoe or shoes movable into contact with the pulley and arranged to be engaged by the toggle-arms and connections, substantially as set forth.

10. In a baling-press, the combination of the framing, the toggle-arms, the pulley, the brake-shoes arranged in position for engagement by the toggle-arms, whereby they may be forced into engagement with the pulley, and having handle-like portions, by which they may be moved out of braking position, substantially as set forth.

11. In a baling-press, the combination of the press-box having a discharge-opening, a gate for closing said opening, latches arranged at the opposite sides of the machine and arranged

to engage said gate, levers connected at their outer ends to the latches, and having their inner ends connected with an operating lever or levers, substantially as set forth.

12. In a baling-press, the combination of the press-box, the gate for closing the discharge-opening thereof, the latches for engaging said gate, the levers R R, connected at their outer ends with the latches, and the operating lever or levers connected with the inner ends of levers R, and extended at their outer ends to the opposite sides of the press-box, substantially as set forth.

13. The combination, in a baling-press, of the press-box, the gate for the discharge-opening thereof, the latches for securing said gate closed, the levers R R, pivotally supported and having their outer ends connected with the latches, the operating lever or levers, and connection between said operating lever or levers and the levers R, substantially as set forth.

14. The combination, in a baling-press, of the press-box, the gate for closing the discharge-opening thereof, the latches r, the levers R, connected at their outer ends, the handle-lever S, connected with the inner ends of the levers R, and the lever S', connected with lever S, such levers S S' being extended at their outer ends to the opposite sides of the press-box, substantially as set forth.
